United States Patent Office

Des. 198,414
Patented June 9, 1964

198,414

KOREAN TYPE FONT

Jackson Burke, New York, N.Y., assignor to Eltra
Corporation, a corporation of New York

Filed Nov. 22, 1961, Ser. No. 67,649

Term of patent 14 years

(Cl. D64—12)

FIG. 1a is a face view of a Korean type font, showing the consonants of my new design;

FIG. 1b is a face view of the vowels thereof;

FIG. 2a is a face view of the double consonants thereof;

FIG. 2b is a face view of the compound vowels; and

FIG. 2c is a face view of the digraphs thereof.

I claim:

The ornamental design for a Korean type font, as shown.
